[57] CLAIM

The ornamental design for a grip for a video camera, as shown and described.

DESCRIPTION

FIG. 1 is a bottom perspective view of a grip for a video camera showing our new design;

FIG. 2 is a left side elevational view thereof;

FIG. 3 is a right side elevational view thereof;

FIG. 4 is a bottom plan view thereof;

FIG. 5 is a top plan view thereof;

FIG. 6 is a side elevational view thereof;

FIG. 7 is a side elevational view opposite of that shown in FIG. 6;

FIG. 8 is a bottom perspective view thereof, the grip being in an unfolded position; and,

FIG. 9 is a bottom perspective view, the legs being in an extended position.

FIG. 1

FIG. 2

FIG. 3
